UNITED STATES PATENT OFFICE.

LOUIS ILLMER, OF CORTLAND, NEW YORK.

INTERNAL-COMBUSTION ENGINE.

Application filed November 20, 1920. Serial No. 425,345.

To all whom it may concern:

Be it known that I, LOUIS ILLMER, a citizen of the United States, and resident of Cortland, in the county of Cortland and State of New York, have invented a new and useful Improvement in Internal-Combustion Engines, of which the following is a specification, reference being had to the accompanying two sheets of drawings, forming part thereof.

My invention relates to internal combustion engines, more particularly to engines of the so-called scavenging type, and has for its object to increase the efficiency of the engine by providing the same with a simple and reliable pumping means which is incorporated in the design of the engine proper and serves to augment the power cylinder capacity of the engine (whether oil 15 or gas) by increasing the air content of the working charge held within the confines of the power cylinder, and also serves to thoroughly scavenge the power cylinder as well.

Another object of the invention is to provide the power cylinders of internal combustion engines with individual pumping units which are contained and embodied in the design of the engine proper and are formed and operated primarily from the 20 working parts thereof.

Another object of the invention is to provide the power cylinders of internal combustion engines with air charging and scavenging means which is self-contained, automatically operated, and is preferably formed between the working mechanisms of twin units having opposed cranks.

Still another object of the invention is to provide a common power cylinder with an air supply which is obtained through the operations of two opposed pumping cylinders communicating with and discharging into said power cylinder; said pumping cylinders being preferably designed to be inter- 25 communicative and provided with a common suction valve which serves as the supply inlet therefor.

Other objects and advantages of the invention will be gathered from the description following herein and considered in connection with the accompanying drawings wherein the invention is shown embodied.

The terms employed herein are used in the generic and descriptive sense to designate the elements illustrated, and are there-

fore not primarily intended as terms of limitation.

In order to illustrate my invention I have shown, without being limited thereto, an embodiment thereof in the accompanying drawings, wherein:

Fig. 1 represents in the main a longitudinal, sectional view taken through a vertical twin cylinder two-stroke oil engine of the single acting type supplied with my invention;

Fig. 2 represents a sectional view taken on line 2—2 on Fig. 1;

Fig. 3 represents a sectional view taken on line 3—3 on Fig. 2;

Fig. 4 represents a sectional view taken on broken line 4—4 on Fig. 1;

Fig. 5 represents a view showing the inlet valve of the device "open";

Fig. 6 represents a plan view of the engine shown in Fig. 1; and

Fig. 7 represents a sectional view taken on line 7—7 on Fig. 2.

Like reference numerals refer to like parts throughout the several views of the drawings.

For convenience the similar and corresponding parts of the two engine units will be distinguished from each other by the use of the suffixes "a" and "b."

The numerals 10^a and 10^b (Fig. 1) represent in their entirety the duplicate twin power cylinders of the engine unit shown and which cylinders are preferably made separate and are provided, respectively, with the upper water-jackets 11^a and 11^b, and the lower clearance jackets 12^a and 12^b, which are open at the bottom to the precompression or base chambers 13^a and 13^b of the power cylinders 10^a and 10^b, which are provided with the base flanges 14^a and 14^b at the bottoms thereof, and the headers 15^a and 15^b at the tops thereof. Each power cylinder, as 10^a, is further provided with the inlet and exhaust ports 16^a and 17^a, respectively, which communicate with the combustion chamber 18^a of the cylinder. Each cylinder is provided with a port, as 19^a, which communicates with the valve chamber 20^a of the valve casing 21^a which is provided with the spring closed automatically operated suction valve 22^a.

23^a represents the power piston which is preferably of the skirt or barrel type and which is designed as in a two-stroke engine 110

to unport both the inlet and exhaust ports 16^a and 17^a when in its lower position, as shown in Fig. 2, and to cover and seal said ports when in its upper position, as indicated by 5 the position of the power piston 23^b in Fig. 1.

24^a represents a stationary seal-plate which is preferably provided with the low pressure stuffing box 25^a and the communicating ports 26^a and serves as a header for the lower or 10 compression end of the power cylinder 10^a.

27 represents a common frame housing which is supported and securely coupled with the common bed plate 28 of the engine, as shown in Fig. 2; said frame housing 27 being 15 preferably provided across the top thereof with the separate air compartments or reservoirs 29^a and 29^b which are separated by the common partition wall 30. The common frame housing 27 is preferably provided with the integrally cast crosshead guide bores or crosshead chambers 31^a and 31^b which are aligned with the power cylinders 10^a and 10^b, respectively, and which pass through the reservoir sections of said 20 frame housing, as shown in Figs. 1 and 2, and which reservoir sections are provided with the reservoir ports 32^a and 32^b and the seal-plate ports 33^a and 33^b, respectively; the latter ports registering with the seal-plate 25 ports, as 26^a shown in Fig. 2.

34 represents the common crank-shaft of the engine which is rotatably supported in the bearings 35 provided therefor in the bed-plate 28, as shown in Fig. 1. 36^a and 36^b 35 represent the cranks of said crank-shaft which are used, respectively, with the power cylinders 10^a and 10^b, and are oppositely positioned at 180° apart, as shown in said Fig.

1. 37^a represents a piston type of crosshead 40 which slidably operates within the crosshead guide bore 31^a and is coupled with the power piston 23^a by the piston rod 38^a, which works through the seal-plate 24^a, and the crank 36^a by the pitman or connecting rod 39^a, as shown in Figs. 1, 2 and 4. 40^a represents the oil injection or check valve and 41 represents the common exhaust pipe of the engine. The power cylinder head 15^a may be made integral with the cylinder proper or 45 separate and securely coupled therewith, as indicated in the drawings. The power cylinders are securely bolted to the frame housing 27 with the seal-plates, as 24^a (Fig. 2) set between the cylinder and the frame housing. The reservoirs 29^a and 29^b serve primarily as conduits to cross-connect the cross-head chambers of one engine unit with the compression or base chamber of the power cylinder of the other engine unit. 50

60 Having thus described the parts of my invention in detail, it will be noted that the crosshead bore 31^a is open through the ports 32^a to the reservoir 29^a and that the latter is open through the seal-ports 33^b registering 65 with the seal-plate ports 26^b to the clearance

chamber 12^b and the precompression chamber 13^b. Wherefore, the suction valve 22^b of the power cylinder 10^b communicates with the crosshead bore 31^a of the power cylinder 10^a, and further, when the inlet ports 16^b are 70 opened by the piston 23^b unporting the same the crosshead bore or chamber 31^a is put into direct communication with the combustion chamber 18^b of the power cylinder 10^b.

Similarly the crosshead chamber 31^b is 75 cross-connected through the reservoir 29^b with the combustion chamber 18^a and communicates therewith through the power cylinder inlet ports 16^a. Thus it will be noted that the piston crosshead, as 37^a, of one engine unit cooperates with the power piston, as 23^b, of the other unit, and therefore, because of the opposed crankage therebetween, when the power piston is traveling upward, its cooperating crosshead piston is traveling simultaneously downward, and vice versa, which accordingly expands or contracts the clearance volumes therebetween. Consequently it will be observed that each engine cylinder is thus provided with an independent charging device which functions as follows: 80

First, it will be noted that the functioning of the parts of the power cylinders 10^a and 10^b are identical and operate as follows: Assuming that the parts are in the positions shown in Figs. 1 and 2 of the drawings and that the two power pistons are moving in opposite directions, as indicated by the arrows (Fig. 1), the piston 23^a has just passed its outer dead center position, while the piston 23^b has just passed its inner dead center position. 95

The working charge confined within the combustion chamber of the cylinder 10^b is 105 under maximum compression and the fuel oil has just been injected through the spray valve 40^b and ignited either by high mechanical compression or by other suitable means such as a spark or hot plate (not shown).

Thus the upward stroke of the power piston, accompanied by the downward stroke of its cross-connected and cooperating cross-head piston, expands the clearance volume of the pump unit which supplies the power cylinder of said power piston and sets up a suction against the suction valve of said pump unit which automatically opens the valve to atmosphere and the pump unit becomes charged with air; that is, the suction action set up by the opposed pistons of the pump unit charges the precompression and clearance chambers of the power cylinder, the crosshead bore, and the reservoir connecting the latter with the precompression and clearance chambers of the power cylinder. 115

Also, the downward stroke of the power piston, accompanied by the upward stroke of the cooperating crosshead piston of the 120

pump unit, closes the suction valve of the pump unit automatically, contracts the clearance volume of the pump unit, and slightly precompresses the air charged in the 5 pump unit by the previous or suction stroke. Then when the power piston unports the inlet ports of the power cylinder, which takes place at the lower end of the downward travel of said power piston, the combustion chamber of the power cylinder is 10 thus opened into direct communication with the pump unit associated therewith and the precompressed air therefrom is discharged into said combustion chamber. The employment 15 of the crosshead feature, as herein disclosed, in connection with the pump unit, adds just so much more to the available supply of air to be used in charging and scavenging the power cylinders of the engine. Ordinarily in the usual two-stroke 20 types of engine the supply per cylinder is limited to the displacement of the power piston, which has been found to be inadequate to provide the full benefits of the scavenging operation. As must be obviously 25 understood, the within type of pump unit incorporating the crosshead piston displacement, in addition to the power piston displacement, is thus supplemented with an 30 amount of air equal to the displacement volume of said crosshead piston over and above the usual power piston displacement; wherefore the said supplemental quantity of air added to the normal quantity of air allowed 35 by the power piston displacement provides an augmented discharge of air within the combustion chamber of the power cylinder, which discharge positively assures a sufficient air flow to thoroughly scavenge the 40 power cylinder and effectively displace the products of combustion so as to insure a practically unpolluted working charge for the combustion of the injected fuel. This 45 greater cleanliness of the scavenged working charge further results in a more perfect and rapid combustion, and thus serves to improve the thermal efficiency of the engine.

Naturally the venting of the base chamber (as 13^a) together with its cross-connected reservoir (as 29^a) and the crosshead chamber (as 31^a) will therefore force a charge of air into the combustion chamber (as 18^b) of the power cylinder (as 10^b) which is materially larger than could be obtained when working with the power piston displacement alone.

The gain in cylinder power capacity, due 60 to the larger air content retained within the cylinder bore volume lying above the power piston at the instant of exhaust closure, far more than compensates for the relatively small power loss involved in augmenting the air charge by means of the described cross-head piston.

The within invention is applicable to any of the ordinary types of gas or oil engines, and serves to improve the thermal efficiency thereof without in any way changing or impairing the regular functioning of the 70 engine.

It will thus be noted that the within invention may be readily incorporated into the design of the ordinary types of twin cylinder engines and may be formed within 75 and from the engine parts proper without complicating or disturbing any of the usual characteristics of the engine. The novel pumping feature of the within disclosed invention provides an efficient and economical 80 scavenging device for internal combustion engines, and yields an increased air content within the confines of the power cylinder as well.

It will thus also be noted from the above 85 disclosure that the pumping elements required for scavenging the power cylinder are kept extremely simple and that the increased power rating accruing from its use 90 may be absorbed without advancing the first 90 cost per unit of power output.

It will also be understood that while I 95 describe the suction valves 22^a and 22^b as being open to atmosphere, the same may be connected differently, as to a source of supply containing air, gas, or mixtures thereof, or other elastic fluid medium according as may be desired.

While the preferred embodiment of my 100 invention has been described in detail, it will be understood that I do not wish to be limited to the particular construction set forth, it being apparent that the described method utilizing the crosshead displacement to supplement the power cylinder air content may readily be applied to both gas and oil engines of either the two or four stroke type.

Having thus set forth my invention, what I claim as new and desire to secure by 110 Letters-Patent is:

1. In an internal combustion engine having a plurality of power cylinders each having a compression and a crosshead chamber, a pump unit comprising a compression chamber of one power cylinder cross-connected to communicate with a crosshead chamber of another power cylinder, a common suction valve adapted to supply said pump unit with working fluid, and means for discharging the delivery of said pump unit into the respective combustion chamber of the power cylinder for charging and scavenging purposes.

2. In a twin cylinder internal combustion engine having a piston type crosshead provided for each cylinder, a pump unit comprising a compression chamber of one of said twin cylinders, a crosshead chamber of the other of said cylinders, and a conduit means cross 120 125 130

- connecting said compression and said cross-head chambers; a fluid supply valve communicating with said conduit; and means for discharging the delivery of said pump unit into the respective combustion chamber of the power cylinder for charging and scavenging purposes.
3. In combination with a twin cylinder internal combustion engine, having opposed
- 10 cranks and piston type crossheads operating in cylinder guides; means enclosing said cylinder guides to form sealed crosshead chambers; means enclosing the power cylinders of the engine for forming base or compression chambers under the respective power pistons thereof; conduit means for cross-connecting the crosshead chamber of one engine cylinder with the compression chamber of the other engine cylinder; a
- 15 common suction valve adapted to supply working fluid to said cross-connected cross-head and compression chambers; and means for discharging and transferring said fluid from said cross-connected crosshead and
- 20 compression chambers into the combustion chamber of a power cylinder of the engine for charging and scavenging purposes.
4. An internal combustion engine of the reciprocating type, comprising a set of power cylinders housing oppositely actuated power pistons therein which are each coupled with a piston type of crosshead operating in cylinders provided therefor; means dividing off the base parts of said power cylinders from the parts of said crosshead cylinders to form compression and crosshead chambers, respectively, for the respective power and crosshead cylinders; means for cross-connecting said crosshead chambers with the
- 25 compression chambers of the opposite power cylinders for establishing connection therebetween; means for supplying said respective cross-connected chambers with working fluid; and means for discharging said fluid from said cross-connected chambers into the combustion chamber above the respective compression chamber for charging and scavenging said combustion chamber.
5. An internal combustion engine having
- 30 a pair of power cylinders, each provided with an exhaust, a power piston and a piston rod, a crank mechanism for reciprocating said piston rods in unison, said mechanism comprising a pair of piston crossheads
- 35 sliding in guide bores provided therefor, means serving to separate each of said guide bores from the bores of said power cylinders to form crosshead and base chambers, respectively, the latter lying beneath the power
- 40 pistons and discharging to their respective intake valves, and means establishing communication between the base chamber of one power cylinder and the crosshead chamber of the other power cylinder; said last
- 45 named crosshead chamber discharging
- through the intake valve of the first named power cylinder.
6. In an internal combustion engine a pair of power cylinders, each provided with an intake valve, a power piston and a piston rod, a crank mechanism for reciprocating said piston rods in unison, said mechanism comprising a pair of piston crossheads sliding in guide bores, means serving to separate each of said guide and power cylinder bores into crosshead and base chambers, respectively, conduit means cross-connecting the base chamber of one power cylinder with the crosshead chamber of the other power cylinder, said conduit discharging to the intake port of the first named cylinder, and a common suction valve supplying working fluid to said cross-connected base chamber and crosshead chamber.
7. In an internal combustion engine, a pair of power cylinders, each provided with an intake valve, a power piston and a piston rod, a frame housing provided with guide bores, a crank mechanism for reciprocating said piston rods in unison, said mechanism comprising a pair of piston crossheads, sliding in said guide bores, means serving to separate said guide bore from the bore of said power cylinder into crosshead chambers and into base chambers, respectively, a reservoir formed integral with the frame housing and communicating with both the base chamber of one power cylinder and the crosshead chamber of the second power cylinder, and a suction valve supplying working fluid to the reservoir and means establishing communication between said reservoir and the intake valve of the first named power cylinder.
8. In an oil engine of the scavenging type, a pair of power cylinders, each provided with an intake valve, a power piston and a piston rod, a crank mechanism for reciprocating said piston rods in unison, said mechanism comprising a pair of piston crossheads sliding in guide bores, means serving to separate said guide bores from the bores of said power cylinders into crosshead and base chambers, respectively, the latter discharging to their respective power cylinder intake ports, an air supply means for the base chamber of one of the power cylinders, a conduit cross-connecting said base chamber with the crosshead chamber of the second power cylinder, and an air supply means for the last named cylinder crosshead chamber whereby to augment the air discharge from the base chamber of the first named power cylinder.
9. In a reciprocating oil engine of the scavenging type, a pair of power cylinders, each provided with an intake valve, and a power piston, a crank mechanism for reciprocating said pistons in unison, said mechanism comprising a pair of piston cross-

heads sliding in extended portions of the respective cylinder bores and a pair of piston rods serving to space said crosshead pistons from their respective power pistons, a stationary seal-plate encircling each of the piston rods, a conduit means cross-connecting the chamber formed above said seal-plate in one of the power cylinders with the cross-head chamber formed below said seal-plate of the second power cylinder, and a common suction valve supplying air to said cross-connected chambers.

10. In an oil engine of the scavenging type, a pair of power cylinders, each provided with a cylinder bore, a crosshead extension, an intake valve, a power piston and a piston rod; a crank mechanism for reciprocating said rods in unison and comprising a pair of piston crossheads sliding in said cross-head extensions aligned with their respective cylinder bores; stationary seal-plates encircling said rods intermediate their respective power pistons and piston crossheads for providing compression chambers above said piston crossheads in said cylinder extensions, means for supplying air to the cylinder extension compression chamber of one of the power cylinders, and means for discharging said air into the cylinder bore lying above the power piston of the second power cylinder whereby to augment the air content of the working charge in the last named cylinder.

11. In an internal combustion engine comprising a power cylinder having an intake

valve in the bore thereof, a power piston having a barrel portion adapted to uncover and time said port, a crankshaft mechanism for actuating said piston, a plurality of charging pump chambers each provided with a separate piston member actuated from said crankshaft and serving as a pumping unit, a conduit cross-connecting said pump chambers, a common suction valve supplying working fluid to said pump chambers, and a discharge means conveying the combined pump delivery to said intake port and into the combustion chamber of the power cylinder for charging and scavenging purposes.

12. In an internal combustion engine comprising a power cylinder having an intake port in the bore thereof, a power piston having a barrel portion adapted to uncover and time said port, a crankshaft mechanism for actuating said piston, a pump unit comprising a base compression chamber and a crosshead chamber each provided with separate piston members actuated from said crankshaft, a conduit cross-connecting said chambers, a common suction valve supplying working fluid to said pump unit, and a discharge means conveying the combined pump delivery to said intake port and into the combustion chamber of the power cylinder for charging and scavenging purposes.

In testimony whereof, I hereunto affix my signature, this 13th day of November, 1920.

LOUIS ILLMER.
